Oil Cloth.

JAMES HUTCHISON, OF LANSINGBURGH, NEW YORK,

ASSIGNOR TO JONA. E. WHIPPLE, OF SAME PLACE.

Letters Patent of a design No. 70, dated June 25, 1861.

SPECIFICATION.

TO ALL WHOM IT MAY CONCERN:

Be it known, that I, JAMES HUTCHISON, of Lansingburgh, in the county of Rensselaer and State of New York, have invented or produced a new and original design for Oil Cloths; and I do hereby declare that the following is a full, clear, and exact description of the same, reference being had to the annexed drawing making a part of this specification, said drawing showing one complete square of the design and four quarter sections of its adjoining squares.

This design may be described as being formed of outline or skeleton squares, composed of links *a*, connected at the corners or angles by oak leaves *b* and acorns *c*.

Within each square there is a quadrilateral figure *A*, having round corners *d*, and just within said figure there is an outline or stripe *e*, which corresponds to the contour of the figure *A*. Within the central figure *A*, at its centre, there is a sprig of lilies *f*, (the lily of the valley,) while at the corners of said figure there are roses and leaves *g*.

The figures *A*, shown in quarter sections, have the same contour or outline as the central one, but the devices within are different.

The small corner figures *h* are composed of the convolvulus (morning glory) with its leaves, while a sprig and buds *i* are at the centres of said figures *A*.

Having thus described my invention, what I claim as new, and desire to secure by Letters Patent, is—

The general configuration of the within described parts to form a new and original design for oil cloths.

JAMES HUTCHISON.

Witnesses:

DANIEL KING,
J. E. WHIPPLE.
